FEEDING DOLL

Julius Weih, Ozone Park, N. Y.

Application December 24, 1936, Serial No. 117,473

10 Claims. (Cl. 46—141)

This invention relates to feeding dolls, and has for one of its objects the provision of such a doll having a rotatable member mounted in the interior of the head thereof, which, when actuated for 5 rotation will sweep or wipe off any food particles on a spoon or other eating implement into the mouth of the said doll.

Another object of the invention is the provision of such a doll having a conduit located directly 10 under the said rotatable member and terminating in a food holding receptacle near the bottom of the doll body for holding any food articles fed to the doll.

A further object of the invention is to provide 15 the said food holding receptacle with an exit opening through which it may be emptied of such food particles when the doll is laid on its back or held with its back facing downwardly.

A still further object is the provision of spring 20 detent means for holding the rotatable member in position ready to be actuated for rotation.

Yet another object of the invention is the provision of a doll embodying my improvements, said doll having a movable arm holding a spoon or the 25 like which may be made to pick up food particles and by manipulation of the arm carry same to the mouth of the doll where the spoon is forced against a tongue simulating vane or blade on the rotatable member to rotate same through an arc 30 sufficiently great enough so that a second blade on the rotatable member may sweep the food from the spoon into the conduit.

Another object is to produce a device of the character described in which the maximum simplicity of construction and operation is secured.

Other objects and advantages will appear as the nature of the improvements is better understood, the invention consisting substantially in the novel arrangement and co-relation of parts 40 herein fully described and illustrated in the accompanying drawing, wherein similar reference characters are used to describe corresponding parts throughout the several views, and then finally pointed out and specifically defined and 45 indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive, standpoint.

The inventive idea involved is capable of receiving a variety of mechanical expressions, one

of which, for the purpose of illustration, is shown in the accompanying drawing, in which—

Figure 1 is a fragmental front elevation of a doll embodying my invention;

Fig. 2 is a sectional view thereof on line 2—2 Fig. 1 with some of the parts shown in end elevation;

Fig. 3 is an enlarged sectional view of the rotatable tongue simulating member, the supporting bracket therefor and conduit, and also showing the spring detent for maintaining the said rotatable member in position.

Fig. 4 is a top plan view partly in section taken on line 4—4 Fig. 2 with the mouth opening of the doll shown at the top and the rear wall of the rotatable member supporting bracket at the bottom of said view.

Fig. 5 is a cross sectional view of a modified form of the rotatable member.

Referring now to the drawing in detail 10 indicates a doll having a body 11 provided with jointed arms 12 only one of which is shown, and a hollow head 13. The arm 12 may be articulated at the shoulder 14, elbow 15, and wrist 16.

Secured to the interior of the head is a bracket 17 in the side arms 18 of which there is rotatably mounted a shaft to which is suitably secured a spoked member 20 preferably made of suitable rubber, the said member having tongue simulating blades or vanes 21, the said member 20 being held against accidental rotation by means of a detent 22 secured to one end of a spring 23 suitably secured to the bracket 17.

The bracket 17 is provided with a bottom wall 24 having an opening 25 in which there is located 35 the funnel shaped mouth 26 of a conduit 27 provided at the bottom thereof with a food receiving receptacle 28 having an exit 29 extending outwardly through the rear of the doll body 11. The bracket sidewalls 18 may each be provided with 40 ears 30 through each of which a nail or pin 31 may be driven to secure the bracket to the head 13 at and directly to the rear of the mouth opening 32 of the doll head.

To adapt the doll so that it may pick up food, 45 one hand 34 thereof may be provided with a spoon or other implement 35. With particles of food in the spoon 35, the arm 12 may be manipulated so that the said spoon is brought into the mouth opening 32 and pressed against one of the tongue 50 simulating vanes or blades 21. The pressure thus exerted against the said blade will cause the member 20 to rotate through a ninety degree angle in the direction of the arrow 36 Fig. 3. During the aforementioned rotation the upper blade 55

- 21 will sweep or wipe the food 37 out of the spoon 35 into the conduit 27 through its mouth opening 26. The food particles 37 will pass through the conduit and come to rest in the receptacle 28. 5
5 When the said receptacle is full, it may be emptied by turning the doll so that the exit 29 points downwardly.

In Fig. 5, I have shown a modified form of the food wiping or sweeping member. In this form of 10 my invention the said sweeper comprises a hub 40 which may be made of wood, composition or other rigid material and may be provided with extensions or fins 41 each supporting a wiper member or strip 42 made of pliable material such 15 as felt, rubber, etc. etc.

From the foregoing it will be seen that I have provided a feeding doll of simple construction which will hold the interest and amuse children as well as grownups.

20 I desire it understood that the tongue simulating or food wiper mechanism may be installed into dolls in which the arms are not articulated and the doll may be fed and the said wiper mechanism may be operated directly by the child.

25 Having described my invention what I claim as new and desire to secure by Letters Patent is:

1. A device of the nature described comprising a bracket adapted to be secured in the interior of a doll's head, a food sweeping member rotatably 30 supported on the said bracket, a plurality of spaced apart radially extending wipers on the said member and detent means for maintaining the said member against accidental rotation.

2. A device of the nature described comprising 35 a bracket adapted to be secured in the interior of a doll's head, a food sweeping member rotatably supported on the said bracket, a plurality of spaced apart radially extending wipers on the said member, detent means for maintaining the 40 said member against accidental rotation, a conduit below the said rotatable food sweeping member, and a food receiving receptacle at the end of the conduit.

3. A device of the nature described comprising 45 a bracket adapted to be secured in the interior of a doll's head, a food sweeping member rotatably supported on the said bracket, a plurality of spaced apart radially extending wipers on the said member, detent means for maintaining the 50 said member against accidental rotation, a conduit below the said rotatable food sweeping member, and a food receiving receptacle at the end of the conduit, the said receptacle having a food exit opening.

4. In a doll having a body and a head, the said 55 head having a mouth opening, a bracket secured to the interior of the head, a food sweeping member rotatably supported on the bracket in alignment with the mouth opening, a plurality of radially spaced apart wipers on the said member and detent means for maintaining the said member against accidental rotation so that the wipers are in proper operating position with relation to the mouth opening.

5. In a doll having a body and a head, the said 60 head having a mouth opening, a bracket secured to the interior of the head, a food sweeping mem-

ber rotatably supported on the bracket in alignment with the mouth opening, a plurality of radially spaced apart wipers on the said member, detent means for maintaining the said member against accidental rotation so that the wipers are 5 in proper operating position with relation to the mouth opening, a conduit one open end of which is below the said rotatable food sweeping member, a receptacle at the opposite end of the conduit, and a food exit passage leading from the receptacle outwardly of the doll body. 10

6. In a doll having a body, a head provided with a mouth opening and an articulated arm, a bracket secured to the interior of the head, a food sweeping member rotatably supported on the bracket in alignment with the mouth opening, a plurality of radially spaced apart wipers on the said member, detent means for maintaining the said member against accidental rotation so that the wipers are in proper operating position with 15 relation to the mouth opening, and a feeding implement supported by the arm for delivering food to the mouth opening and to actuate the sweeper member for rotation.

7. In a doll having a body, a head provided with 20 a mouth opening and an articulated arm, a multi-bladed wiper member rotatably mounted in the interior of the head in alignment with the mouth opening, detent means for maintaining the said member against accidental rotation, and a feeding implement supported by the arm for delivering food to the mouth opening and to actuate the sweeper member for rotation. 25

8. In a doll having a body, a head provided with a mouth opening and an articulated arm, a pliable 30 multibladed sweeper member rotatably mounted in the interior of the head in alignment with the mouth opening, detent means for maintaining the said member against accidental rotation, a feeding implement supported by the arm for delivering food to the mouth opening and to actuate the sweeper member for rotation, a conduit 35 one open end of which is below the said rotatable food sweeper member, a receptacle at the opposite end of the conduit, and a food exit passage 40 leading from the receptacle outwardly of the doll body. 45

9. In combination with a doll having a hollow head provided with a mouth opening, a sweeper member rotatably mounted in the interior of the head adjacent the mouth opening, and pliable wiper blades extending radially from the said 50 sweeper member.

10. In a doll having a body, a head provided with a mouth opening and an articulated arm, a sweeper member rotatably mounted in the interior of the head in alignment with the mouth opening, a feeding implement supported by the arm for delivering food to the mouth opening and to actuate the sweeper member for rotation, a conduit one open end of which is below the said 55 rotatable food sweeper member, a receptacle at the opposite end of the conduit, and a food exit passage leading from the receptacle outwardly of the doll body. 60

JULIUS WEIH.
